UNITED STATES PATENT OFFICE.

FREDERICK WILLIAM SCHROEDER, OF LONDON, ENGLAND, ASSIGNOR TO THE MARINE
AIR-PULSION COMPANY, A CORPORATION.

PROPELLING VESSELS.

986,766.

Specification of Letters Patent. Patented Mar. 14, 1911.

Application filed July 17, 1907. Serial No. 384,193.

To all whom it may concern:

Be it known that I, FREDERICK WILLIAM SCHROEDER, of the city and county of London, England, have invented a new and useful Improvement in Propelling Vessels, of which the following is a full, clear, and exact description, reference being had to the accompanying drawing, forming part of this specification, in which—

10 Figure 1 is a longitudinal section of a vessel equipped with my invention; Fig. 2 is a plan view of same; Figs. 3 and 4 are vertical cross sections on lines III—III and IV—IV, respectively, of Fig. 1; Fig. 5 is a 15 modification of vertical section on the line IV—IV of Fig. 1; Fig. 6 shows detail of propulsion tube; Figs. 7 and 8 show a portion of side and rear elevation of modified type of vessel.

20 My invention relates to the propulsion of vessels by means of the escape of compressed air or gases acting against the water and provides a layer of air or gas between the water and the hull of the vessel in order to 25 diminish friction, such layer of air being formed by forcing compressed air or gas through openings or vents formed along the whole length of a tube or tubes arranged on the under side or bottom of the vessel. The 30 action of the air or gas is such that it tends to lessen the displacement when the vessel is in motion. I also construct openings in the tubes of such a character as will enable the escape of the air or gas either toward the 35 bow or toward the stern, and which by the ensuing reaction of the water will increase the speed of the vessel in one direction or the other; and I separate the bottom of the vessel or a section thereof into a series of compartments open at the bottom by means of a 40 number of small plates or projections from the bottom of the vessel, or from the propulsion tubes.

The accompanying drawings show forms of 45 vessels built in accordance with this invention, but it is to be understood that the principle of my invention can be applied to vessels or ships of other construction.

Referring to the drawings, the vessel 1 is 50 of an especial construction, having a very broad bottom 2 with sides 3, 3' and deck 4, and has bow 5 and stern 6 of any construction desired. The vessel is preferably made of great length and beam in comparison with

its tonnage, so that it will be of comparatively light draft even when at rest. Along the bottom 2 are arranged a series of longitudinal tubes, 7, 7', each of which is provided with small vents or openings 8, 8' distributed along the entire length of the tube, 55 and directed rearwardly and downwardly. These tubes are preferably separated each from the other, but may be divided into groups, by means of longitudinal projections or plates 9 depending from the bottom of the 60 vessel or from the tubes arranged thereon (as shown in Fig. 3) to a depth sufficient to retain the air or gas from lateral motion even when the vessel careens to the greatest 65 possible extent. Said tubes 7, 7' and projections 9, preferably have tapered ends 10, 70 11, respectively, so as to diminish the frictional resistance of the water.

The vessel is preferably constructed with a central keel 12 and two outside keels 13 75 and 14 at the section in which the propulsion tubes 7, 7' are located. These outside keels may be constituted by the ship's framing and are preferably deeper in order to protect my apparatus from snags and the like, 80 and also to protect it when beached or put in dry dock since the said keels then form a support which holds the bottom clear. The bottom of the ship, which is for the most part of the type usual for shallow 85 draft vessels and approximately parallel with the water line, is slightly inclined upward toward the stern, but gradually becoming arched into two preferably concave arches, as shown in Fig. 3, on line III—III 90 of Fig. 1.

15, 15' are gas engines or other suitable motive power, driving pumps 16, 16' which deliver the air or gas at suitable pressure to the reservoir 17. This reservoir 17 communicates by pipes 18, 18' with transverse headers or supply pipes 19, 19' which lead to the longitudinal tubes 7, 7' through a connecting pipe or union 20. For the purpose of supplying the propulsion tubes, 7, 7', 95 100 the more readily with gas or air, the connecting pipe or union 20 is preferably of approximately twice the cross-sectional area of the immediate tube connected therewith, and is located near the middle of said tube. 105

When the tubes 7, 7' are supplied with compressed air or gas the reaction of the jets issuing from the rearwardly-inclined

openings 8, 8' and the upwardly-directed pressure of the air or gas forces the vessel forwardly and upwardly over the water in a straight line, and when the air or gas supply is reduced or cut off by valves 21 or 22, 22' from either the port or starboard tubes, the progress of the vessel will be to port or to starboard, respectively.

For the purpose of backing or going astern, a similar arrangement of apparatus can be made, but having tubes 7, 7' with openings 8 forwardly directed so that the issue of air or gas from said forwardly-directed openings will propel the vessel astern, and the steering can be effected by reducing or cutting off the air or gas supply from either series of tubes so arranged, but it is not being usually necessary to have as large motive power for going astern as for going ahead, I show in Figs. 1, 2 and 4 a modification of my invention for the purpose of sending the vessel astern, which consists in two tubes placed either side of the keel near the bow and with bilge-keels 12', 12'' projecting from the bottom of the vessel outside said tubes, said tubes having forwardly-directed orifices and connected with a header 19' or transverse piping having controlling valves 22' therefor, and with the header connected with the reservoir 17 in the manner described above.

In Fig. 5 I show a modification of apparatus for going astern which consists in a tube with forwardly-directed openings placed in an open hollow keel toward the bow of the vessel and operated as above.

Fig. 6 shows detail of tubes with vents or openings 8 directed opposite to direction of propulsion and of greater cross-sectional area at their outer than at their inner surface, and with ends thereof tapered so as to present a smaller frictional surface to the water.

Figs. 7 and 8 show a modification of my invention especially adapted for deep-draft vessels. In this construction I place the propulsion tubing 7, upon the inclined stern of the vessel, which is preferably constructed with a series of arched grooves opening outward somewhat like a fan as they run aft and upward. In these grooves are placed the longitudinal propulsion tubes 7, through which the air or gas is forced as previously described, and out of the usual openings 8, distributed along the entire length of the tubes. These fan-shaped longitudinal grooves give opportunity for an expanding pressure of the air or gas as it

seeks to escape and is forced against the vessel by the water.

It is to be understood that my invention is not restricted to the forms shown and described in the specification, but that various other constructions may be used without departing from the scope of my invention.

What I claim is:

1. Apparatus for propelling vessels, consisting of a vessel having a series of longitudinal tubes placed under the bottom of the vessel, which tubes are provided with inclined openings directed oppositely to the direction of propulsion and having projections depending therefrom, and means for propelling the vessel by forcing air or gas therethrough; substantially as described. 75

2. Apparatus for propelling vessels, consisting of a vessel having a series of longitudinal tubes placed under the bottom of the vessel, said tubes having suitable openings and tapered ends presenting little frictional resistance to the water, and having projections depending therefrom with ends also inclined to the taper of the tubes, and means for propelling the vessel by forcing air or gas therethrough; substantially as described. 85

3. Apparatus for propelling vessels, consisting of a vessel having a plurality of series of parallel, longitudinal tubes placed under the bottom of the vessel, which tubes are provided with inclined openings directed oppositely to the direction of propulsion, and having projections depending therefrom, and means for propelling the vessel by forcing air or gas therethrough; 95 substantially as described.

4. Apparatus for propelling vessels, consisting of a vessel having a series of longitudinal tubes placed under the bottom of the vessel, which tubes are provided with inclined openings directed oppositely to the direction of propulsion and having projections depending therefrom, said projections forming separate channels or open chambers for holding the air or gas issuing from the immediate tube and the tube adjacent thereto, and means for propelling the vessel by forcing air or gas through said tubes; 105 substantially as described.

In testimony whereof I have hereunto set my hand.

FREDERICK WILLIAM SCHROEDER.
